UNITED STATES PATENT OFFICE.

THOMAS A. COLEMAN, OF VREDENBURGH, ALABAMA, ASSIGNOR OF ONE-HALF TO
PETER VREDENBURGH, JR., OF VREDENBURGH, ALABAMA.

CONVEYER-FLIGHT.

1,182,458.

Specification of Letters Patent.

Patented May 9, 1916.

Application filed February 10, 1915. Serial No. 7,276.

To all whom it may concern:

Be it known that I, THOMAS A. COLEMAN, a citizen of the United States, residing at the town of Vredenburgh, county of Monroe, 5 and State of Alabama, have invented a certain new and useful Improvement in Conveyer-Flights, of which the following is a full, clear, and exact description, such as will enable others skilled in the art to which 10 it appertains to make and use the same, reference being had to the accompanying drawings, forming part of this specification.

My invention relates to flights for chain conveyers of a type commonly employed in 15 connection with the various mills for the purpose of conducting away scrap or refuse material.

The principal objects of my invention are, to provide a form of flight which may be 20 easily manufactured and supplied at low cost; which obviates the necessity of manufacturing a variety of types; which may be used on either the right side or the left side of the chain; which does not require the use 25 of any rivets or bolts; and which may be readily attached to the chain without requiring the chain's being slackened.

Other objects will be obvious or herein-after pointed out.

30 In the drawings, Figure 1 represents a plan view of a portion of a conveyer equipped with my improved form of flights. Fig. 2 is a detail illustrating the mode of applying the flight to the chain. Fig. 3 is 35 a detail showing the rear portion of a flight as it appears when attached to a chain. Fig. 4 is a perspective illustration of the flight. Fig. 5 is a different perspective illustration of the flight. Fig. 6 is a top view of a modification. Fig. 7 is a section on line 7-7 of Fig. 6.

As is well known in the art in connection 45 with many mills, a conveyer is employed which consists generally of a chain or similar flexible member which is moved longitudinally by a suitable mechanism, and which carries flights projecting either at one or both sides thereof and traveling in a trough or chute. Material delivered into the chute 50 is carried forward by the flights in the direction of movement of the chain to the desired point of delivery.

In Fig. 1 of the drawings, I have illustrated a portion of such conveyer in which 55 1 represents the chute or trough, 2 the chain,

4 a sheave over which the chain travels, and 5 flights which are attached to the chain. Various forms of flights are in use, some of which require the use of bolts, rivets, or similar fastening means to secure them to the 60 chain, and other forms which, while not requiring the use of rivets or bolts, require that the chain be slackened in order that they may be attached thereto. Because of the nature of the material which these 65 conveyers are required to handle, and by virtue of the fact that the chains are customarily long and the chains and actuating mechanism necessarily heavy, the consideration of repair is an important one and one which 70 must be frequently met in practice.

It is my purpose to provide a form of flight which may be attached to the chain without the use of any separable fastening means, and which may be attached to the 75 chain without requiring any slackening up of the same, which latter is attended with considerable difficulty due to the weight of the chain and various conveyer parts.

My improved flight is cast integrally of 80 malleable iron and is formed with the customary wing 6 which projects to the side of the chain and co-operates with the trough or chute into which the material is delivered. The wing 6 projects from a body portion 85 7 which on the side opposite the wing terminates in a butt member 8. Adjacent the body portion 7 the butt member is provided with a top groove 9 and a bottom groove 10. The height and width of the butt member is 90 such as will permit its being introduced through a link of the conveyer chain, the thickness between the top and bottom grooves is such as to permit the groove portion to turn a quarter revolution in the link 95 on the longitudinal axis of the flight. A part of the body portion 7 extends to the rear of the wing member 6 and of the butt member 8, and is provided with the lugs 11 which are spaced so as to fit between the sides of 100 the link and make close contact therewith. Adjacent the lugs 11, the body portion 7 forms bearing shoulders 12 which are adapted to abut the link. The portion of the butt member 8 adjacent the grooves 9 and 10, 105 likewise forms bearing shoulders 14 which are adapted to abut the opposite side of the link.

In attaching the flight to the chain on the right hand side thereof, the flight is turned 110

with its face downward, and the butt portion 8 introduced through the link. The flight is then turned slightly out of perpendicular relative to the chain, and then is rotated on its longitudinal axis so as to bring the face of the wing into position perpendicular to the bottom of the chute. This brings the lugs 11 into position where they may be introduced between the sides of the link by 5 swinging the flight to bring the wing into perpendicular position relative to the chain. The lugs 11 are then bent over by hammering so as to engage the sides of the link, as best illustrated in Fig. 3, which causes the shoulders 12 to firmly abut the lateral portion of the link, and secures the flight in place. This operation also causes the bearing shoulders 14 to abut the link on its opposite side. In operation, when the flight encounters material on the chute, the pressure tends to 10 wedge the flight more firmly in place, due to the leverage resulting from the disposal of the bearing shoulders relative to the wing. The bearing shoulders on the butt portion 8 being substantially in line with the wing, and the bearing shoulders 12 being behind the same, it will be seen that the pressure of material against the wing forces the bearing shoulders 14 and 12 firmly against the 15 opposite sides of the link, and relieves the lugs 11 of all stress.

In using the flight on the left side of the chain, it is turned with its face upward so as to permit the introduction of the butt portion 8 through the link and then rotated and secured in position as above described.

It is obvious that the form imparted to the butt portion by the grooves 9 and 10 enables this flight to be attached to links of 20 different pitch. Hence the manufacturer requires patterns only for different sizes of chain, and not for different pitches. It is obvious, moreover, that it is not necessary to supply rights and lefts as the same flight 25 may be used on either side of the chain. These manufacturing considerations are of importance when it is remembered that while there are four or five sizes of chain commonly employed, the pitch of the links 30 varies to a much greater extent.

I am aware that the device is capable of alterations and modifications not illustrated herein without departing from the spirit and scope of the invention. For example, 35 instead of forming the lugs 11 integrally on the body portion, they may be replaced by a clamping member overlapping the legs of the link on the side opposite the shoulders 12, and secured by a suitable bolt seated in 40 the body portion between the shoulders 12. In this form, of course, I do not obtain the object above referred to of forming the entire flight integrally and dispensing with separable attaching means. This form is as 45 effective as the form above described in en-

abling the use of the flight on either side of the chain and dispensing with the necessity of slackening the chain in applying the flight. This form is illustrated in Figs. 6 and 7 in which the clamping member 11^a 70 is shown in place to engage the legs of the link, being secured to the body portion 7 by the bolt 15.

What I claim is:

1. A flight for a chain conveyer formed 75 integrally with a body portion, a wing portion extending laterally therefrom, a butt portion extending from the body portion on the side opposite the wing portion, said butt portion being of a size to permit its introduction through the link of a conveyer chain, and grooved to permit a partial rotation of the flight on its longitudinal axis, said butt portion being formed with bearing shoulders adapted to abut one side of 80 the link, the body portion being provided with bearing shoulders adapted to abut the opposite side of the link, and the body portion being formed with malleable lugs which may be introduced within the link 85 and bent to prevent their withdrawal therefrom.

2. A flight for a chain conveyer consisting of an integral member formed with a body portion having shoulders adapted to 90 abut one side of a link of a conveyer chain, a butt portion projecting laterally from the body portion and introducible within such a link, said butt portion being adapted to permit a partial rotation of the flight within 95 the link and having bearing shoulders adapted to abut the side of the link when the flight is in operative position, a member formed on the body portion and adapted to engage the link to prevent rotation of the 100 flight, and a wing member extending laterally from the body portion.

3. In combination with a conveyer chain, a flight integrally formed and having a body portion provided with shoulders 110 adapted to abut a side of a link, a butt portion insertible within a link and provided with shoulders adapted to overlap and abut the opposite side thereof upon partial rotation of the flight, members on the body 115 portion adapted to prevent rotation of the flight relative to the link, and a wing extending laterally from the body portion.

4. In combination with a conveyer chain, a flight having a wing portion and a butt 120 portion extending laterally therefrom, said butt portion being insertible through a link and rotatable to a position in which it overlaps opposite sides of the link, said flight having a portion for engaging the link to 125 prevent rotation of the flight relative thereto.

5. In combination with a conveyer chain, a flight having a portion insertible through a link and movable therein by rotation of 130

the flight on its longitudinal axis to a position in which its withdrawal from the link is prevented, and means affixed to the flight adapted to engage the chain to prevent rotation of the flight relative thereto.

6. In a chain conveyer, a flight having a portion insertible through a link and partially revoluble therein on the longitudinal axis of the flight, and means attached to the flight adapted to engage the chain to pre-

vent rotation of the flight on its longitudinal axis.

In testimony whereof I hereunto affix my signature in the presence of two witnesses, this 6th day of February, 1915.

THOMAS A. COLEMAN.
